UNITED STATES PATENT OFFICE.

GEORGE HANDLEY, OF PALMERS GREEN, ENGLAND, ASSIGNOR OF ONE-HALF TO
PERCY WILLIAM BULLOCK, OF LONDON, ENGLAND.

ROTARY PUMP WITH EJECTOR.

1,418,921.

Specification of Letters Patent. Patented June 6, 1922.

Application filed November 23, 1920. Serial No. 426,039.

(GRANTED UNDER THE PROVISIONS OF THE ACT OF MARCH 3, 1921, 41 STAT. L., 1313.)

To all whom it may concern:

Be it known that I, GEORGE HANDLEY, a subject of the King of Great Britain, residing at Palmers Green, in the county of 5 Middlesex, England, have invented new and useful Improvements Relating to Rotary Pumps with Ejectors, (for which I have filed application in Great Britain Nov. 13, 1919, Patent No. 159,258), of which the following is a specification.

As is well known, in the operation of a centrifugal pump, the liquid in passing therethrough acquires potential energy which at the outlet from the pump exists 10 largely as pressure. On the other hand, in a rotary displacement pump, the energy stored in the liquid at the outlet from the pump is largely kinetic and, consequently, this type of pump has only a low efficiency 15 when working against low heads. Heretofore it has been proposed to provide an arrangement in which liquid from a force pump is delivered through the nozzle of an injector device whereby additional liquid is 20 drawn into the delivery pipe to mingle with that which has passed through the pump. This known arrangement is advantageous in some instances, for example, in pumping from wells or bore holes, by reason of the 25 particular situation from which the liquid is to be raised. The use of an injector device in combination with a pump of the reciprocating or oscillating type, does not however suggest that a rotary displacement pump 30 can be made more economical and efficient in operation by providing an injector device arranged in combination therewith so as to usefully employ the kinetic energy of the liquid issuing from the pump since the 35 potential energy of the issuing liquid in other forms of pump may exist as pressure and therefore may not be so susceptible of being usefully taken out by directing this liquid through the nozzle feed pipe of an 40 ejector.

Now it has been found by experiment that this kinetic energy can be very efficiently utilized to draw in additional liquid to mingle with the effluent from the pump by 45 conducting the effluent through an ejector device of the Venturi tube type, and this invention provides a pumping installation wherein a rotary displacement pump has

arranged in combination therewith in the delivery pipe leading from the pump an 55 ejector device of the Venturi tube type operating to draw in additional liquid to mingle with that discharge from the pump chamber.

In the accompanying drawing which 60 shows how the said invention may be conveniently and advantageously carried into practice:—

Figure 1 is a view showing a rotary displacement pump having a Venturi tube 65 ejector device arranged in combination therewith in accordance with this invention.

Figure 2 is a view illustrating a modified arrangement.

As shown in Figure 1, *a* is a rotary displacement pump having an outlet at *b* to which is connected a short length of pipe *c* having a collar *d* screwed thereon. A gland *e* is formed between this collar and the pipe *c* in which a cone *f* is mounted. 75 The other end of this cone is screwed in an aperture in the wall of a jet chamber *g* and holds in place a nozzle *h*. This construction enables the cone *f* to be easily removed so that the nozzle *h* can be changed for one 80 of a different size if desired. The nozzle *h* extends into the jet chamber the wall of which is made in two parts and a branch connection *i* for an auxiliary suction pipe opens at an angle into the lower part of the 85 said chamber.

The upper part of the jet chamber is provided with an outlet *k* directly opposite to and in line with the nozzle *h*. Fitting to this outlet is a pressure cone *l* converging 90 in the direction of flow of the liquid from the pump, to a narrow throat *m* of a Venturi tube and from thence increasing in diameter to that of the delivery pipe *n* to which it is joined.

The operation of these parts is as follows:—Liquid leaving the pump outlet *b* passes into the cone *f* which conserves and increases its velocity which becomes a maximum at the mouth of the nozzle *h*. Crossing 100 the jet chamber *g*, by virtue of its velocity, the jet of liquid passes into the throat *m* of the pressure cone *l* creating a partial vacuum in the jet chamber. A stream of liquid is therefore drawn into the jet chamber 105 through the suction pipe *j* and branch *i*,

and the combined streams are forced through the throat m into the diverging or expanding part of the cone and into the delivery pipe n .

- 5 The liquid drawn in through the suction pipe j may be of a different nature from that issuing from the nozzle h , in any case where it is desired that two different liquids shall mix whilst being pumped.
- 10 In the modified arrangement shown in Figure 2 which shows the invention applied for the purpose of raising water from a well o , a rising main p is provided leading from the lowest level from which water is to be raised and emptying into a tank q placed above the inlet to the pump a' . The latter is placed in an inverted position, that is to say, with the inlet above and the discharge below, or the pump may be specially constructed for this purpose with the inlet and discharge openings in the required positions. A conduit r is provided for leading a supply of liquid from the tank q to the pump, the surplus liquid accumulating in the tank being led away through an outflow pipe s .
- 15
- 20
- 25

The pump a' imparts energy to a stream of water or other liquid which is forced through a downcast or descending pipe t running parallel with and beside the rising main p . The pipes t , p may if desired be arranged one within the other. At its lower end the pipe t terminates in an upwardly directed nozzle u arranged to project a stream of liquid from the pipe t at a high velocity into the throat v or constricted portion of a Venturi tube w which is formed on the lower end of the rising main p and serves as an ejector device or augmentor. The partial vacuum thereby created raises the liquid surrounding the lower open end of the Venturi tube w and lifts it into the throat v where it comes into contact with the stream issuing from the nozzle u and is carried into the rising main p . This portion of the contrivance is an adaptation of a known device, called a jet pump, by which a certain quantity of liquid can be made to set in motion a much larger quantity by reason of its superior pressure head.

It will be seen that the rotary pump a' does not act directly on the liquid to be raised from the bottom of the well o , but operates through the medium of the liquid propelled through the downcast pipe t . The advantage of this arrangement is that the pump can be installed at the surface of the ground, only the downcast pipe t , augmentor w and rising main p being placed in the well. For excessive depths a number of augmentors can be arranged in stages so that the pressure in the pipes need not exceed that required to lift the liquid from stage to stage.

The advantage of the inverted arrangement of pump is that liquid from the container or tank can flow directly into the inlet, thus enabling the pump to be run at a higher speed than if a suction supply is provided. Also, the pump delivery being beneath, enables the pump to be placed directly over the downcast pipe, thus avoiding loss of velocity by bends in the pipe. This is a special advantage in the case of rotary pumps which impart their rotary or centrifugal velocity to the water. For pumps of the positive rotary type the supply can be strained off from the main outflow.

The improved arrangements hereinabove described can be applied to raising fluids as well as liquids.

What I claim is:—

The combination, with a rotary displacement pump, of a Venturi tube ejector, which is arranged in the outlet conduit of said pump and comprises a jet chamber having a shouldered socket, a nozzle fitting into said shouldered socket in said jet-chamber, a conical tube having its smaller end engaging said shouldered socket in said jet-chamber, and a gland connected to the outlet of said pump and securing the larger end of said conical tube.

Signed at London, England this 10th day of November, 1920.

GEORGE HANDLEY.

In the presence of—

HERBERT A. BEESTON,
E. MURPHY.
